UNITED STATES PATENT OFFICE

GEORGE W. MACKENZIE, OF BEAVER, PENNSYLVANIA, ASSIGNOR TO CORRECT MEASURE COMPANY, OF ROCHESTER, PENNSYLVANIA, A CORPORATION OF PENNSYLVANIA

ELECTRIC METER PUMP

Application filed September 30, 1929. Serial No. 396,116.

This invention relates to improvements in meter pumps or the like employed for dispensing of gasoline, etc.

It is among the objects of this invention 5 to provide a meter pump of simple and durable mechanical construction and which shall be efficient in its operation of dispensing liquid, and which shall be adapted to correctly measure and indicate the quantity of liquid 10 dispensed thereby.

Another object of the invention is to provide means for simultaneously controlling the main valve and the pump drive mechanism and which shall be adapted to lock said 15 mechanism in its inoperative position when the metering device is not in use.

These and other objects will become more apparent from a consideration of the accompanying drawings in which like reference 20 characters designate like parts and in which Fig. 1 is a front elevational view of a metering pump with the housings removed and embodying the principles of this invention; Fig. 2 is a side elevational view thereof; Fig. 25 3 is a detail view partly in section and partly in elevation illustrating the method of locking the nozzle and pump operating mechanism; Fig. 4 is a cross sectional view of a combination switch and valve for controlling 30 the drive mechanism and the valve; Fig. 5 is an end elevational view thereof; Figs. 6 and 7 are top, plan and cross sectional views, 35 respectively, of a by-pass valve employed in the system and Fig. 8 is a cross-sectional view partly in elevation of a combined strainer and valve employed in the structure in the manner hereinafter described.

With reference to Figs. 1 to 3 inclusive, of the drawings, the structure therein illustrated 40 comprises a base 1, an upper support 2, vertical supporting rods 3 and an upper and lower housing 4 and 5 respectively.

Supported within the lower housing is a strainer 6 illustrated in Fig. 8 of the drawings having the connection 7 leading to the storage tank from which the fluid is pumped and having a branch 8 connected to an upright pipe 9 and a by-pass connection at 10 which connects to the by-pass valve 11, which 50 latter by an upright connecting pipe line 12

communicates with an expansion chamber 13. The connecting line 9 of the strainer is secured to the inlet connection 14 of a fluid pump 15 which is provided with a passage 55 communicating at 16 with the by-pass line 12 and a connection at 17 with a control valve generally designated at 18 and which is more clearly illustrated in Figs. 4 and 5 of the drawings.

The pump 15 is supported on a bracket 19 60 that is clamped to the uprights 3 and a motor 20 is secured to the underside of the support 19 and operatively connected by a chain drive 21 with a sprocket wheel 22 that is mounted to rotate with the pump shaft 23. The control valve 18 is connected by pipe 24 65 to a meter 25 carrying an indicating dial 26 and the meter is connected by pipe line 27 to a visible flow indicator 28 to which a flexible hose is connected at 29.

Mounted on the upper housing 4 is a dome 30 having a light bracket 31 secured thereto provided with sockets 32 for receiving an electric light bulb and a socket 33 is provided for lighting the face of the meter dial. The 70 electric lights are controlled by a switch 34 provided with a switch box 35 which is connected by a conduit 36 to the upper lights and a conduit 37 to a conduit box 38, the latter being connected to another conduit box at 39 75 and thence to a source of electrical current.

As shown in Fig. 4, a motor switch 40 is provided for controlling the drive motor 20, this switch being operated by a plunger 41 in response to the rotary movement of a cam 42 which latter is secured to a cam shaft 43 that is controlled in its angular movement by a lever 44 which is manipulated through an operating rod 45 shown in Figs. 2 and 3.

A second cam 46 is secured to the shaft 43 to operate the control valve 18, this valve being controlled with the operation of the motor switch 40 through the cam 42. The control valve is provided with a check valve which consists of a ball 47 secured on the flared end 48 of a tube 49 and retained in its position in which it is movable by the lower face of the valve 18. A recess 50 is provided in the valve in which the ball 47 may be displaced to permit drainage of fluid through 95 100

the tube 49. The ball 47 seats on the flanged end 48 of the tube when the fluid pressure acts upon the external side of the valve 18. A packing gland 51 is provided to prevent leakage of the fluid from the valve through the crank shaft connection.

As shown in Figs. 6 and 7, the by-pass valve 11 consists of a valve ring 52, the lower face of which constitutes a seat against which 10 the valve 53 rests in its connected position and against which it is biased by the coil spring 54.

In Fig. 8 the strainer 6 is illustrated as provided with a valve 55 which is constructed to be seated against the pressure column 15 of the valve and adapted to rise in response to fluid passing upwardly through the valve passage.

The passage of valve 55 is cut off from the 20 main passage by a filter screen 56 through which the fluid must pass when it is drawn from the source or storage tank by the pump 15.

As shown in Fig. 3 of the drawings, a nozzle 57 is secured by a flexible hose 58 leading to the connection 29 of the flow indicator and the nozzle is adapted to rest in a hood 59 provided on top of the pump when not in use. In this position, the nozzle bracket 60 and the 30 operating lever 61 are adapted to pass over a hook 62 which is provided with a perforation or opening 63 for receiving a pad lock whereby the nozzle may be locked in its inoperative position. To place the nozzle mechanism on the hook 62 it is necessary to depress the latter to its lowermost position, thereby depressing the operating rod 45 to the position where 35 the cam shaft 43 is rotated to shut off the motor switch 40 and the main valve 18.

40 The operation of the meter pump is briefly as follows:—With the nozzle 57 removed from hook 62 the latter is lifted to rotate cam shaft 43 by raising the operating rod 45 and turning the crank or lever 44 that is secured to the cam shaft 43. When so raised, switch 40 is operated to energize the pump motor 20 and simultaneously the valve 18 is depressed by its cam 46 to the open position. When the pump is actuated the fluid is drawn 45 through the strainer 6, the valve 18, and from the valve 18 through the upper connection 24 to the meter 25 from which it passes through line 27 to the visible flow indicator, thence through the connection 29 of the flexible hose 58 to the nozzle 57. The meter dial indicating the volume of fluid passing through the meter, responds to the flow as long as the nozzle valve is open and when the valve is closed by releasing the valve handle 61, the 55 pump may be still operated without registering flow through the meter on account of the by-pass connection at 16 and 12 leading from the pump to the strainer 11. When the nozzle 57 is subsequently hung on the hook 60 60 65 62, the latter is lowered whereby the oper-

ating rod 45 is depressed to operate switch 40 through the cam 42 of the cam shaft, thereby deenergizing the drive motor 20.

By this arrangement, the motor and operating valve are controlled through the operating lever whereas the flow of fluid is independently controlled through the nozzle lever 61. With the locking mechanism previously described, both the motor control and fluid control are rendered inoperative since the operating lever and nozzle lever are both locked against movement.

It is obvious from the foregoing description of this invention that metering pumps made in accordance therewith, provide positive and expedient means for dispensing gasoline or the like in a minimum of time and with absolute control of the quantity of the fluid being dispensed by the apparatus.

Although one embodiment of the invention has been herein described and claimed, it will be obvious to those skilled in the art that various modifications may be made in the details of construction without departing from the principles herein set forth.

I claim:

1. In a liquid dispensing device comprising in combination a pump connected to a storage tank, electrical apparatus for operating said pump, an electric switch for controlling said pump, a control valve disposed in said outlet connection and an operating shaft provided with means for actuating said switch and valve and an operating rod connecting said shaft for actuating the latter, said rod being provided with means for engaging the dispensing nozzle whereby it is depressed to actuate the operating shaft.

2. In a liquid dispensing device comprising in combination a pump connected to a storage tank, electrical apparatus for operating said pump, an electric switch for controlling said pump, a control valve disposed in said outlet connection and an operating shaft provided with means for actuating said switch and valve and an operating rod connecting said shaft for actuating the latter, a valved nozzle secured to the outlet connection and means for locking the nozzle to said rod to render the pump control mechanism inoperative.

In testimony whereof I have hereunto set my hand and seal this 5 day of August, 1929.

GEORGE W. MACKENZIE.
